UNITED STATES PATENT OFFICE.

RICHARD G. JOHNSON, OF LEAD, SOUTH DAKOTA.

TIE-PLATE.

1,189,117.

Specification of Letters Patent. Patented June 27, 1916.

Application filed April 18, 1916. Serial No. 92,015.

To all whom it may concern:

Be it known that I, RICHARD G. JOHNSON, a citizen of the United States, residing at Lead, in the county of Lawrence and State 5 of South Dakota, have invented certain new and useful Improvements in Tie-Plates; and I do hereby declare the following to be a full, clear, and exact description of the invention, such as will enable others skilled in the art to which it appertains to make and use the same.

The primary object of this invention is to admit of the fastening spikes employed for holding a tie plate on a wooden tie being 15 securely held in operative position and prevented from working loose.

Another object of the invention is the provision of a tie plate having means associated therewith for penetrating the tie, said means 20 being adapted to compress the fibers of the tie at the point of insertion of the spike, so as to increase the frictional engagement between the spike and the tie.

Other objects will appear and be better 25 understood from that embodiment of my invention of which the following is a specification, reference being had to the accompanying drawing forming a part thereof, in which:

30 Figure 1 is a bottom plan view of the plate removed from the tie, Fig. 2 is a side view thereof, Fig. 3 is a transverse section taken through one end of the plate, and showing the fiber compressing means in op- 35 erative position in the tie.

Referring to the drawing in detail, the numeral 1 designates a rectangular shaped tie plate adapted to be mounted on the upper side of a tie, at one end thereof, as shown 40 in Fig. 3 of the drawing. The upper side of the plate 1 is provided with a transverse rib 3 designed to engage the adjacent longitudinal edge of the base flange of the rail, not shown. The plate is provided, at one 45 end, with a pair of spike-receiving openings 4, and is provided adjacent its opposite ends with another spike-receiving opening 5, the latter opening extending through the plate and the rib 3. Depending from the under 50 side of the plate 1 are pairs of fiber compressing members 6 and 7. The fiber compressing members forming the pair 6 are of lengths considerably greater than the length of the members forming the pair 7, and are

located on opposite sides of the opening 5, 55 and in spaced relation thereto, and as shown in Fig. 1 of the drawing, the said members have their inner ends converging and terminally spaced from each other. The other pair of fiber compressing members are located 60 between the openings 4 and are arranged in converging relation and have their inner ends spaced from each other. The members forming the pairs 6 and 7 have their lower edges sharpened, as shown 65 at 8, and the members forming the pair 6 have their opposed inner faces beveled, as shown at 9, and have their outer faces straight, as shown at 10, and the members forming the pair 7 have their outer surfaces 70 beveled, as shown at 11, and their inner surfaces or faces straight, as shown at 12. The compressing members forming the pairs 6 and 7 are mounted on the plate in such relation to the openings 4 and 5, that when 75 the members penetrate the tie the fibers displaced by the beveled faces will be crowded beneath the openings 4 and 5, so that the spikes, designated 13, when driven into the tie will meet with considerable resistance, 80 and the frictional engagement between the spikes and the tie will be increased so as to maximize the anchorage of the spikes.

Having thus described my invention what I claim as new is:

1. The combination with a wooden tie, of a plate mounted on the upper side of the tie and provided with spike-receiving openings, and spaced pairs of converging tie penetrating and fiber compressing members 90 carried by the under side of the plate and located adjacent the openings.

2. The combination with a wooden tie, of a plate mounted on the upper side of the tie and provided with spike-receiving openings, spaced pairs of tie-penetrating and fiber compressing members carried by the under side of the plate and located between the openings, the penetrating members forming one pair being of a greater length 100 than the members forming the other pair.

In testimony whereof I affix my signature in presence of two witnesses.

RICHARD G. JOHNSON.

Witnesses:

CHARLES R. GROTHJOHN,
WILLIAM K. MORRISON.
